UNITED STATES PATENT OFFICE.

WILLIAM B. HARLAN, OF CHURCHVILLE, MARYLAND.

FURNITURE.

1,053,384.

Specification of Letters Patent. Patented Feb. 18, 1913.

Application filed March 28, 1912. Serial No. 686,880.

To all whom it may concern:

Be it known that I, WILLIAM BEATTY HARLAN, citizen of the United States, residing at Churchville, in the county of Harford and State of Maryland, have invented 5 certain new and useful Improvements in Furniture, of which the following is a specification.

This invention relates to furniture and 10 has special reference to sectional bookcases.

Sectional bookcases have become very 15 popular and are extensively used, but when the tiers of sections meet at the corner of a room considerable space is lost owing to the fact that the front corners of the bookcase 20 sections meet in advance of the side walls of the room, and it is not possible to place one section between the end of the meeting section and the wall of the room because the door of the section thus arranged could not 25 then be opened. The space between the ends of the sections and the walls of the room is consequently not utilized under present conditions, but is permitted to accumulate dust and dirt in which disease breeding germs may generate.

It is the object of my invention to provide 30 an article of furniture which will be simple in construction and not expensive to produce, by which this space may be utilized, and which will harmonize in its appearance with the bookcases between which it is fitted.

A preferred embodiment of my invention 35 is illustrated in the accompanying drawings, and the invention consists in certain novel features which will be hereinafter fully described and then particularly pointed out in the claims following the description.

In the drawings: Figure 1 is a perspective view of a structure embodying my invention showing the same as it appears when set up for use. Fig. 2 is a detail sectional perspective view of a portion of the device the spring being partly broken away. Fig. 3 is a detail horizontal section.

In carrying out my invention, I provide a casing consisting of inner or back walls 1 arranged at such an angle to each other as will fit against the meeting walls of the room and corresponding to the angle formed by the said walls. These walls 1 may, of course, be formed in continuous 5 members of a height corresponding to that of the most generally employed columns of

bookcases, but my invention contemplates making the same in sections corresponding to the bookcase sections. The front walls 2 which extend from the front edges of the back walls, at right angles thereto, have the same width as the end walls of the bookcase sections, so that their front edges do not meet but leave an open space, indicated at 3, whereby access may be had to the interior of the compartment or cupboard formed by the side walls. A top 4 and a base 5 are also provided which will be finished in a manner to harmonize with the bookcase sections, against which the device is placed, 60 and present the appearance of a continuation of the said sections. A door or closure will be provided to extend across the open space 3 between the front edges of the front side walls 2, and this closure may, of course, 65 be of any desired construction. I prefer, however, to employ the door illustrated in detail in Figs. 2 and 3 as the same furnishes a neat closure for the compartment and economizes space. This door comprises a 70 front or closing member 6 from the upper and lower ends of which project radial arms 7 provided at their inner ends with slots 8 adapted to engage pivot pins 9 secured at the centers of the top 4 and base 5, as will 75 be readily understood. A lug or stop 10 is provided on each arm 7 and a spring 11 is arranged between the pivot pin 9 and the said lug and supported by the same, said spring serving by its expansion to hold the 80 beveled side edges 12 of the door in contact with the inner surfaces of the front side walls 2 of the compartment, thereby effecting an air tight closure for the front of the same. When it is desired to obtain access to 85 the interior of the compartment, the door is pushed inwardly against the tension of the spring 11, sufficiently to permit the edges of the door to clear the front side walls, when the door is swung about the pivot pins, and 90 the door is then swung to either side to the position indicated by dotted lines in Fig. 3, thereby uncovering the open space 3 so that 95 articles may be placed in or removed from the compartment or cupboard.

It will be readily seen from the foregoing 100 description, taken in connection with the accompanying drawings, that I have provided an exceedingly simple and inexpensive closet or compartment, which may be set in the corner of a room between adjacent columns of sectional bookcases and in which canes.

umbrellas, rolled maps, or other articles may be conveniently stored. The space, heretofore wasted, is by my invention utilized and is occupied in such a manner that the accumulation of dirt and dust therein is effectually prevented.

- 5 The device may be made in sections adapted to be superposed in exactly the same manner as the bookcase sections are assembled, and the doors may be made in various standard sizes so as to accommodate columns of different heights or they may be made in sections which may be joined into one structure so that the height of the cupboard, and of the door closing the same, may be made to correspond to the bookcases, as the bookcases are arranged and re-arranged to suit the whims or taste of the owner.
- 10 Having thus described my invention, what I claim as new, is:
- 15 1. The combination with a cupboard having converging side walls with their front

edges spaced apart, a door adapted to bridge the space between said side walls, 25 means for supporting the said door and permitting the same to swing, and means for holding the said door yieldably in engagement with the said side walls.

2. In a cupboard, the combination of converging side walls having their front edges spaced apart, a door adapted to bridge the space between said edges and engage the side walls, pivot pins within the cupboard, arms projecting inwardly from the door 35 and provided with slots engaging the pivot pins, and springs bearing upon the pivot pins and upon said arms to yieldably hold the door in engagement with the side walls and across the space between the same. 40

In testimony whereof I affix my signature in presence of two witnesses.

WILLIAM B. HARLAN. [L.S.]
